CLAIM

The ornamental design for a robotic vacuum cleaner, as shown and described.

DESCRIPTION

FIG. 1 is a top view of a robotic vacuum cleaner showing our new design;

FIG. 2 is a bottom view thereof;

FIG. 3 is a left view thereof;

FIG. 4 is a right view thereof;

FIG. 5 is a front view thereof;

FIG. 6 is a rear view thereof; and,

FIG. 7 is a top perspective view thereof.

The broken lines in the drawings depict portions of a robotic vacuum cleaner that form no part of the claimed design.
